UNITED STATES PATENT OFFICE.

GERTRUDE C. HART, OF CHICAGO, ILLINOIS, ASSIGNOR TO PROTESTANT WOMEN'S NATIONAL CIVIC FEDERATION, OF CHICAGO, ILLINOIS, A CORPORATION OF ILLINOIS.

DESIGN FOR A BADGE.

Application filed October 23, 1924. Serial No. 11,155. Term of patent 14 years.

To all whom it may concern:

Be it known that I, GERTRUDE C. HART, a citizen of the United States, residing at Chicago, in the county of Cook and State of Illinois, have invented a new, original, and ornamental Design for a Badge, of which the following is a specification, reference being had to the accompanying drawing, forming a part thereof.

I claim:

The ornamental design for a badge as shown.

In testimony whereof, I have hereunto signed my name in the presence of two subscribing witnesses.

GERTRUDE C. HART.
